UNITED STATES PATENT OFFICE.

ISAAC F. ALLMAN, OF JERSEY CITY, NEW JERSEY.

VAPOR-ENGINE.

SPECIFICATION forming part of Letters Patent No. 556,237, dated March 10, 1896.

Application filed October 11, 1895. Serial No. 565,406. (No model.)

To all whom it may concern:

Be it known that I, ISAAC F. ALLMAN, of Jersey City, in the county of Hudson and State of New Jersey, have invented certain 5 new and useful Improvements in Vapor-Engines, of which the following is a full, clear, and exact description.

The object of the invention is to provide certain new and useful improvements in vapor-engines, whereby the engines are governed with great precision.

The invention consists of certain parts and details and combinations of the same, as will be fully described hereinafter and then pointed out in the claims.

Reference is to be had to the accompanying drawings, forming a part of this specification, in which similar characters of reference indicate corresponding parts in all the figures.

20 Figure 1 is a side elevation of the improvement with the parts in section. Fig. 2 is a sectional plan view of the same on the line 2 2 of Fig. 1. Fig. 3 is a cross-section of the governor on the line 3 3 of Fig. 1, and Fig. 4 is a cross-section of part of the improvement 25 on the line 4 4 of Fig. 1.

The improved vapor-engine is provided with the usual cylinder A, having an exhaust-valve B held normally in a closed position by 30 a spring C coiled on the valve-stem B' and pressing on a collar B² thereon, as indicated in Fig. 2. The outer end of the valve-stem B' is adapted to be engaged by one end of a lever D extending horizontally and fulcrumed 35 at its middle at D' on a bracket E' on the engine-frame E. The other end of the lever D is connected with a rod F provided on its free end with a head F' fitted to slide transversely on a bracket E² held or formed on the engine-frame E. This head F' is formed with a transversely-extending opening or groove F² engaged by the lower end of a lever G extending upwardly and fulcrumed at G' on the frame E.

45 The upper end of the lever G carries a friction-roller G² traveling on the peripheral surface of a cam H held on the face of a gear-wheel H' mounted to turn on a stud H² secured to the engine-frame, and the said gear-wheel H' is in mesh with a smaller gear-wheel H³ secured on the engine-shaft I, connected in the usual manner by a crank-arm and pit-

man with the piston in the cylinder A. The friction-roller G² is held in contact with the cam H by a spring G³ drawing on the lever G. 55 Now it will be seen that when the engine is in motion the gear-wheel H³ on the shaft I causes a revolving of the gear-wheel H', so that the cam H acts on the lever G to impart a swinging motion to the latter in unison with 60 the movement of the piston in the cylinder A.

The head F' is provided with a transverse opening, in which is fitted to slide a bolt or plunger J formed with a reduced portion J' and a wider portion J², so that when the bolt 65 J is in the position shown in Fig. 2—that is, with the reduced portion J' in the path of the lower swinging end of the lever G—then the latter does not move the head F' transversely, and consequently the lever D remains 70 in a fixed position, allowing the spring C to hold the exhaust-valve B closed. When, however, the bolt J is moved laterally in the direction of the arrow a', (see Fig. 2,) then the wider portion J² by moving in the path of 75 the lower swinging end of the lever G is engaged by the latter and a transverse movement of the head F' takes place. This movement of the head F' causes the rod F to act on the lever D to impart a swinging motion 80 to the latter and to open the exhaust-valve B at the required time to permit the burned gases in the cylinder A to escape.

Movement is given to the bolt or plunger J from the governor, and for this purpose the 85 said bolt is secured to a link K, having a universal or double pivotal connection K' K² with the lower end of a lever L, fulcrumed at L' on the frame E and pivotally connected with a second lever L², fulcrumed at L³ on the 90 frame, said levers forming a compound lever for quickly acting on the link K and bolt J, so as to move the portion J² in or out of engagement with the lower end of the swinging lever G. 95

The upper end of the lever L² engages, by a pin L⁴, an annular groove N' in a sleeve N, mounted to slide longitudinally on the shaft I and provided with a second annular groove N², engaged by a pin on the lower end of a 100 lever O, fulcrumed at O' on a bracket attached to a fly-wheel P secured on the engine-shaft I. The fly-wheel P is provided with a rod Q extending radially and outwardly from

- the hub, and on this rod is mounted to slide a block R, pressed on by a spring S coiled on the rod Q, and the said block R is formed with an obliquely-extending groove R' engaged by a pin O² held on the upper end of the lever O. Now it will be seen that when the engine is running at a rate of speed exceeding the normal rate, then the block R will move outward by centrifugal force to cause the lever O to swing, whereby the sleeve N is shifted to the left and a swinging motion is given to the compound lever L² L to draw the bolt J in the inverse direction of the arrow a' to move the wider portion J² out of the path of the lower swinging end of the lever G. When this takes place, the head F' is not affected by the constant swinging motion of the lever G, and consequently the exhaust-valve B will be held in a closed position. Therefore the burned gases within the cylinder A cannot exhaust. As long as the gases cannot exhaust from the cylinder, a new mixture is not drawn in. Consequently further explosions do not take place to propel the piston until the speed of the engine is reduced to a normal rate, at which time the block R will move back into its innermost position by the action of the spring S, so that a reverse movement of the lever O, sleeve N, compound levers L² and L, link K and bolt J takes place to again move the latter transversely in the direction of the arrow a' to bring the wider portion J² in the path of the lower swinging end of the lever G. When this takes place, a sliding motion is again given to the head F', so that the lever D is actuated to open the exhaust-valve B regularly in unison with the movement of the piston in the cylinder A.
- Thus it will be seen that by the invention described the governor acts positively and quickly when an abnormal rate of speed is attained, causing the exhaust-valve B to remain closed, so as to prevent the escape of the burned gases and a drawing of the mixture into the cylinder A until the speed is reduced.
- Having thus fully described my invention, I claim as new and desire to secure by Letters Patent—
1. An engine, provided with a governor, comprising a spring-pressed block mounted to slide on a running part of the engine, and formed with an oblique groove, a lever fulcrumed on the running part and engaging the groove, and a connection from the said lever to the part to be governed, substantially as described.
2. An engine, provided with a governor comprising a spring-pressed block mounted to slide on a running part of the engine and formed with an oblique groove, a lever fulcrumed on the running part and engaging said groove, and a sleeve fitted to slide and connected with said lever and with the part to be governed, substantially as shown and described.

3. An engine provided with a governor, a part to be governed, a movable head controlling the motion of the part to be governed, a lever or bar receiving a to-and-fro motion from the engine and having sufficient play within said head to move without affecting the part to be governed, and a bolt controlled by the governor and mounted to move in the head to limit the play of the said lever and cause the head to move with the lever, substantially as described.

4. An engine, provided with a governor, a part to be governed, a head controlling said part, a bolt controlled by the governor and having a widened portion adapted to pass in and out of the said head, and a lever receiving a constant swinging motion from a running part of the engine, and adapted to engage said widened portion of the bolt, to impart a sliding motion to said head, substantially as shown and described.

5. An engine, provided with a head connected with a bolt having a widened portion and adapted to pass in and out of the said head, a lever receiving a constant motion from a running part of the engine, and adapted to engage said widened portion of the bolt, to impart a sliding motion to said head, a part whose motion is controlled by the said head, and a governor for imparting a sliding motion to said bolt, substantially as shown and described.

6. An engine, provided with a head connected with a bolt having a widened portion and adapted to pass in and out of the said head, a lever receiving a constant motion from a running part of the engine, and adapted to engage said widened portion of the bolt, to impart a sliding motion to said head, a part whose motion is controlled by the said head, a governor for imparting a sliding motion to said bolt, and comprising a spring-pressed block fitted to slide on a running part of the engine and formed with an oblique groove, a lever engaging said groove, a sleeve engaged by said lever and adapted to receive a sliding motion, a compound lever connected with said sleeve, and a link for connecting said compound lever with said bolt, as set forth.

7. An engine provided with a governor, a part to be governed, a movable head controlling the motion of the part to be governed, a lever or bar receiving a to-and-fro motion from the engine and having sufficient play within said head to move without operating the head, and a bolt slidable in the head at an angle to the path of travel of said lever and provided with a portion adapted to be projected into the path of travel of the lever to limit its play and cause the head to move with the lever, said bolt being operatively connected to the governor, substantially as described.
